UNITED STATES PATENT OFFICE.

OTTO J. HEMSCHEMEYER, OF FAIRVIEW, MONTANA.

BARREL-CLOSURE.

1,283,177.

Specification of Letters Patent. Patented Oct. 29, 1918.

Application filed August 31, 1916. Serial No. 117,914.

To all whom it may concern:

Be it known that I, OTTO J. HEMSCHEMEYER, a citizen of the United States, residing at Fairview, in the county of Richland 5 and State of Montana, have invented certain new and useful Improvements in Barrel-Closures, of which the following is a specification.

My invention relates to a reusable closure 10 particularly for barrels.

At the present time barrels are often used as shipping receptacles, for instance for the return of bottles. In order to gain access to the interior, the barrel head or closure is 15 usually broken and damaged with the result that it cannot be reused. It is under such conditions that my invention is chiefly applicable since the closure or head may be readily removed without damage to the head 20 or to the barrel, and with equal facility replaced and reused when desired.

I particularly aim to provide a closure capable of spreading under the action of a wedge; one having an opening to facilitate 25 insertion of the wedge, and to be closed by a filler block and to provide a means to fasten the wedge and block securely and removably in place.

With the above, and additional objects, 30 such as will be pointed out as the description hereinafter progresses, the invention has been embodied in one preferred form as illustrated in accompanying drawings, wherein:

Figure 1 is a top or plan view of a barrel 35 having my improved closure associated therewith;

Fig. 2 is a view similar to Fig. 1 with the latch leaf and protecting plate removed but suggested by dotted lines and parts being 40 partly shown in section;

Fig. 3 is a top or plan view of the barrel closure alone;

Fig. 4 is a detail side elevation of the fastening means for the barrel closure;

Fig. 5 is a longitudinal sectional view 45 through the fastening means for the barrel closure, and

Fig. 6 is a cross sectional view on the line 6—6 of Fig. 1.

Referring specifically to the drawings, 50 wherein like reference characters designate like or similar parts, the invention has been shown in connection with a barrel 7 having a groove 8 adjacent the top in order to receive a closure or head. My improved

closure or head comprises similar sections 9 collectively substantially forming a disk and each section being made if desired of a plurality of strips of wood or other material fastened together as by means of cleats 10 60 and rivets 11. The sections, however, may be made in any desired manner and of any suitable material.

The head 9—9 is cut away to provide intermediate the sections, a wedge receiving 65 opening 12 which leads from an opening 13 at the center of the barrel and tapers or decreases in size toward the marginal edge of the closure. Adjacent the opening 13, a link 14 bridges the sections and is pivotally 70 connected to each section as by means of rivets or the equivalent at 15. This connection of link and pivots enables the sections 9—9 of the closure to move relatively to a slight extent; that is spread. 75

In order to spread the sections 9—9, I employ a wedge 16 conforming in shape to the opening 12. To prevent descent of the wedge into the barrel, I preferably provide longitudinal tongues 17 on the sections 9 80 which enter grooves 18 in the sides of the wedge. In order that the wedge may be inserted and positioned, the opening 13 is provided and the wedge is first placed with the widest portion in this opening and then the 85 grooves are moved into receiving engagement with the tongues 17. After inserting the wedge, the opening 13 is again unfilled or open and in order to prevent withdrawal of the wedge, I provide a filler block 19 90 which extends into the opening 13. To prevent descent of the filler plug 19 into the barrel through the opening 13 and to protect the block 19 and the opening 13, I provide a plate as shown at 20 which is fastened 95 as by means of rivets 21 to the block 19 and which overlaps the sections 9.

In order to fasten the filler 19 in the opening 13 against accidental removal, a suitable fastening means is provided, which 100 is preferably in the form of a hasp 22. This hasp is fastened in position in any suitable manner and may be clamped intermediate the filler 19 and the plate 20, with at least one of the rivets or fastenings 21 extending 105 through the hasp. One arm of the hasp is pivoted or hinged to the wedge 16 at 23. As a result, the hasp, filler 19 and plate 20 are all pivoted from the wedge. The lateral arms of the hasp extend beyond the plate 110

19 and staples 24, fastened to the section 9, extend up through and beyond the arm so that fastening pins or the like 25 may be passed through the staples above the hasp. 5
5 In use, after the barrel has been filled, the head is positioned so that the same will extend into the groove 8 of the barrel 7. Since the sections 9 are pivoted at 15, they may be moved relatively to facilitate such 10 insertion. After the head has thus been positioned, the wedge 16 is positioned with its larger end in the opening 13 wherupon the wedge is moved from the center in the opening 12 and with the grooves 18 receiving the 15 tongues 17. When this insertion occurs, the fastening device is preferably in the dotted line position of Fig. 4 so that the filler 19 will be above the opening 13 and will not interfere with the insertion. As the wedge 20 is moved outwardly, it will spread the sections 9 from the members 15 as pivots. After being inserted, plate 20 is depressed so that filler 19 will extend into the opening 13, thus completely closing the head and preventing withdrawal of the wedge. There- 25 after the pins or fastening members 25 are positioned in the staples 24 and as a result accidental unfastening of the head is prevented. It will be understood that in order 30 to remove the head, the pins 25 are removed, plate 20 and filler 19 moved outwardly, and then used as a handle so as to slide the wedge inwardly into the opening 13 for withdrawal. My construction is capable 35 of reuse and is operable without injury to it or to the barrel.

Since merely the preferred embodiment of the invention has been illustrated and described, it is to be understood that changes 40 in the details of construction may be re-

sorted to within the spirit and scope of the appended claims.

I claim:

1. An expandible closure having a wedge shaped opening extending inwardly from the marginal edge and being narrowed at the margin, said opening at the inner extremity being enlarged, a wedge member insertible into said opening through the enlarged extremity thereof, a filler member 50 insertible into the enlarged extremity after positioning of the wedge member, a hasp fastened to one of said members and pivoted to the other of said members, and fastening means on the closure for coöperating with 55 the hasp.

2. An expandible closure having a wedge shaped opening extending inwardly from the marginal edge and being narrowed at the marginal edge, said opening having an 60 enlargement at its inner extremity, an expanding member insertible into said opening through said enlarged extremity, a filler member insertible into the enlarged extremity after insertion of the expanding member, 65 a plate disposed over said filler and overlapping the closure, a hasp secured intermediate the filler and plate and having an arm pivoted to said expanding member, said hasp also having an arm extending beyond 70 the plate, a staple on said closure coöperating with the second mentioned arm, and fastening means coöperating with the staple.

In testimony whereof I affix my signature in presence of two witnesses.

OTTO J. HEMSCHEMEYER.
